(57) **CLAIM**

The ornamental design for a variable speed drive for electric motors, as shown and described.

DESCRIPTION

FIG. 1 is a front view of the variable speed drive for electrical motors;

FIG. 2 is a rear view of the variable speed drive for electrical motors of FIG. 1;

FIG. 3 is a top view of the variable speed drive for electrical motors of FIG. 1;

FIG. 4 is a bottom view of the variable speed drive for electrical motors of FIG. 1;

FIG. 5 is a right side view of the variable speed drive for electrical motors of FIG. 1;

FIG. 6 is a left side view of the variable speed drive for electrical motors of FIG. 1; and,

FIG. 7 is a perspective view of the variable speed drive for electrical motors of FIG. 1.
